UNITED STATES PATENT OFFICE.

SIDNEY PARKER AND JAMES D. BENNETT, OF CHICAGO, ILLINOIS, ASSIGNEES, BY DIRECT AND MESNE ASSIGNMENTS, TO GEORGE H. WATSON, OF ACKLEY, IOWA, ABNER W. MORRILL AND FRED S. MORRILL, OF WATERLOO, IOWA, AND SIDNEY PARKER, OF CHICAGO, ILLINOIS.

SMOKE-CONSUMING APPARATUS.

SPECIFICATION forming part of Letters Patent No. 257,606, dated May 9, 1882.

Application filed January 9, 1882. (No model.)

To all whom it may concern:

Be it known that we, SIDNEY PARKER and JAMES D. BENNETT, both of the city of Chicago, in the county of Cook and State of Illinois, have invented a new and useful Apparatus for Consuming Smoke in Furnaces; and we hereby declare the following to be a full, clear, and exact description thereof, which will enable others skilled in the art to which our invention relates to make and use the same, reference being had to the accompanying drawings, forming a part hereof, and in which—

Figure 1 represents a side view of a steam-boiler and furnace with our apparatus attached. Fig. 2 represents a front view of the same. Fig. 3 represents a front view of the apparatus D with its cover removed. Fig. 4 represents a side view of the apparatus D in section, on the line *x x*, with its cover and inlet and exhaust pipes *f* and *h*. Fig. 5 represents an end sectional view taken on the line *y y*.

Like letters of reference indicate like parts.

The object of our invention is to produce a smoke-consuming apparatus, situated within the furnace of a boiler above the fire, by means of a jet of steam operating upon the flame and gases released from the fuel within said furnace, issuing from said apparatus, substantially as hereinafter specified.

In the drawings, *a* represents a steam-boiler, *b* the side walls of its furnace *O*, and *D* our apparatus placed within the furnace.

e represents the steam-pipe supplying steam to the apparatus, and *f* a globe-valve.

g represents a T-shaped pipe forming the exhaust of the apparatus; *h*, the cover of the apparatus *D*, and *i* a channel around the top of the side walls of the heater *D*, and *j* a corresponding bead on its cover *h*.

h represents the wire screens covering the openings *p*, made at alternate ends through the partition-walls *l*.

The exhaust-pipe *g* has a slot, *m*, extending

along the entire length of the outer side of the T-shaped exhaust.

The top *h* is firmly bolted to the apparatus *D*, and the channel *i* is packed with asbestos or other heat-resisting substance, so as to make a steam-tight joint.

The apparatus *D* is placed on the inside of the furnace-wall, and preferably a little from it, so that heat may pass up between it and the furnace-wall, so as to thoroughly heat it, and thus superheat the passing steam, and thereby give it increased force and dryness by the time it comes in contact with the smoke and gases. The screens *h* retard the steam as it passes from one chamber *n* into another, and thereby subject it to greater heat before it finally emerges from the slot *m*.

The apparatus *D* is made of cast-iron, to which the cover *h* is strongly bolted, as shown, and its place in the furnace may be more or less to the front or rear along the side walls; or a series of them may be fastened to both sides and front of the furnace-walls. A bridge-wall, *c*, is placed across the rear of the furnace for the purpose of retarding the smoke, which would otherwise be urged into the chimney too rapidly and partly defeat the object sought.

What we claim as new is—

The apparatus *D*, formed of one solid piece of cast-iron, and provided with partition-walls *l*, dividing it into chambers *n*, having openings *p* at alternate ends of said chambers, provided with screens, channel *i*, and inlet *f*, in combination with cover *h*, provided with bead *j*, and T-shaped exhaust provided with slot *m*, substantially as specified.

SIDNEY PARKER.
JAMES D. BENNETT
